UNITED STATES PATENT OFFICE

ARNO A. DORST, OF CINCINNATI, OHIO.

DESIGN FOR A RING.

No. 37,916.

Specification for Design.

Patented March 27, 1906.

Application filed February 16, 1906. Serial No. 301,604. Term of patent 7 years.

To all whom it may concern:

Be it known that I, ARNO A. DORST, a citizen of the United States, residing at Cincinnati, in the county of Hamilton and State of Ohio, have invented a new, original, and ornamental Design for a Ring, of which the following is a specification, reference being had to the accompanying drawings, forming part thereof.

Figure 1 is a top plan view of my new design for a ring. Fig. 2 is a side elevation thereof.

I claim—

The ornamental design for a ring, as shown

ARNO A. DORST.

Witnesses:

OLIVER B. KAISER.
LEO O'DONNELL.
